A. G. F. KUROWSKI & J. SOKOLOV.
TYPE WRITING MACHINE,
APPLICATION FILED OCT. 21, 1916.

1,260,687.

Patented Mar. 26, 1918.

UNITED STATES PATENT OFFICE.

ALFRED G. F. KUROWSKI, OF BROOKLYN, AND JACOB SOKOLOV, OF NEW YORK, N. Y.,
ASSIGNORS TO UNDERWOOD TYPEWRITER COMPANY, OF NEW YORK, N. Y., A COR-
PORATION OF DELAWARE.

TYPE-WRITING MACHINE.

1,260,687.

Specification of Letters Patent. Patented Mar. 26, 1918.

Application filed October 21, 1916. Serial No. 126,820.

To all whom it may concern:

Be it known that we, ALFRED G. F. KUROWSKI, a subject of the Emperor of Germany, but having taken out United States naturalization papers, residing in Brooklyn borough, in the county of Kings, city and State of New York, and JACOB SOKOLOV, a citizen of the United States, residing in borough of the Bronx, in the county of the Bronx, city and State of New York, have invented certain new and useful improvements in Type-Writing Machines, of which the following is a specification.

Our invention relates to typewriting machines, and is herein disclosed as applied to an Underwood typewriter. The Underwood typewriter, like many typewriting machines, is provided with a revolvable platen about which the work-sheet or paper is passed, on which the typewritten matter is to be imprinted, and successive lines of this work-sheet are brought up to the printing line by revolving the platen. In most such typewriting machines, it is customary to have the lines of typewriting spaced apart by considerably more than the height of the highest letter in the set of types, and the line-spacing mechanism is usually adjusted to automatically space the lines of writing at a distance apart which is usually desirable. In such machines, however, it is frequently desirable to write a single character or two occasionally, partly or slightly above, or below, the usual line of writing.

Our invention provides means whereby this may be done without materially delaying the operation of writing. We provide means for firmly gripping the typewriter platen, and then turn it to the required extent by a single operation of a handle, the connections being such, that when the handle is released, a spring returns the handle to its normal position, at the same time starting the platen back to the position from which the handle has just previously moved it. The accurate alining of the platen is accomplished by the usual line-space detent, and thus makes the machine ready to continue writing on the normal line.

One advantage of our invention is that only a single handle is required to shift the platen in either direction. This results from the fact that the handle, when drawn toward the spist, rotates the platen backwardly, while the opposite movement of the handle rotates the platen forwardly; both motions being the natural motions in operating such machines.

Other features and advantages will hereinafter appear.

In the accompanying drawings,

Figure 1 is a perspective view of the right-hand end of the usual carriage of the Underwood typewriting machine, showing only so much thereof as seems advantageous for the illustration of our invention.

Fig. 2 is a dissected perspective view of certain members of the clutch.

Fig. 3 is a section through the clutch, showing the relationship of the parts included in Fig. 2.

Fig. 4 is a section through part of one end of the platen, showing the relationship of the seizing band of the clutch to the platen.

Fig. 5 is an end-on view of the parts shown in Fig. 3, when the clutch is released.

Fig. 6 is similar to Fig. 5, but shows the clutch seizing the platen.

Fig. 7 shows the alinement of parts in normal position.

Fig. 8 shows the alinement of parts when the platen is rotated forwardly by the clutch.

Fig. 9 is the same as Fig. 8, but showing the parts having rotated the platen backwardly.

Fig. 10 is a front view of the platen, together with the clutch and operating parts largely in section.

Fig. 11 is a plan view of part of the usual line-space mechanism for rotating the platen.

The platen 1 comprises an outer covering 2, of hard rubber, which may be supported from the shaft 3 in any usual or desired way, by means of an end plate 4, through which passes a number of screws 5, the screws usually entering into the backing 100 of the rubber surface 2. The platen is journaled by means of the shaft 3 in the

ends 6 and 7 of a shift frame 8 in the usual manner, and is provided with the usual line-space wheel 9 on which the usual line-spacing pawl 10 is effective, said wheel also serving as an alining wheel, for which purpose the usual spring detent 11 bears against it, serving to aline the platen at the printing line.

- The typewriting machine also includes
- 10 the usual type-bars 12, comprising types 13, which, in the Underwood typewriter, strike against the front face of the platen through the usual ribbon (not shown), to print the characters 14 on the usual work-sheet 15, which has passed around the platen and is held there in the usual way by pressure rolls (not shown). As the typewriter carriage travels along, the types 13 print thereon in a substantially straight line, unless the line-space mechanism, including the pawl 10, is operated, or unless the platen is turned by one or the other of its knobs 16, which are fast in the usual way at the opposite ends of the shaft 3.
  - 25 If it is desired to print a character a little above or a little below the line, it has usually heretofore been necessary to rotate the platen by means of its knob 16.

According to our invention, the platen

- 30 may be rotated to the desired extent by means of a handle 17, which, in the present disclosure, is shown as adapted to rotate the platen about half the altitude of the smaller letters of the alphabet, so that, if it is desired to write "a", the letter "a" is written in the usual manner, then the handle 17 is pushed rearwardly, and the character "2" is written in the usual manner with the result that the "2" will be
- 40 at the desired point above the line.

To accomplish this, the handle 17 is connected to devices which cause it to seize the platen and then rotate it, if it is moved from the normal position, shown in Fig. 7. These devices include two V-shaped arc rings 19 and 20, which normally ride loosely in the V-shaped groove 21 on the end plate 4 of the platen. When, however, the handle 17 is moved either forwardly or rearwardly, away from its normal position, the two rings 19 and 20 are drawn together, so that they seize the platen and then the continued movement of the handle 17 causes the rings to turn the platen until the handle is arrested by a suitable stop. The amount of this throw of the handle 17, after seizing the platen, determines the level by which the letters will be printed by any type then operated. To make the rings 19 and 20 effective to seize the platen, the recessed end of the ring 20 is pivoted on a pin 22 projecting from the recessed end 23 of the ring 19, and the two rings are drawn together by means of a toggle joint 24, which is straightened out, by the movement of the

handle 17, in either direction. This toggle joint 24 is formed of two links 25 and 26, which are pivotally joined by a stub-shaft 27, said shaft extending through a V-shaped cam opening 28 in a cam plate 29, which is fast to the handle 17, said cam plate and handle for this purpose, being both fast to a shaft 30.

The movement of the handle 17, in either direction, causes the V-shaped cam 28 to draw down the stub-shaft 27, and draw the rings 19 and 20 together, causing them to lock themselves to the platen end plate 4. To accomplish this, the toggle-joint 24 is effective on recessed overlapping portions 34 of the rings 19 and 20, and is joined to the ring 20 by a shouldered screw 31, which, while holding it closely, allows the link 26 of the toggle to swing freely. The other link 25 of the toggle is pivoted to the ring 19, by means of a shouldered screw 32, which passes through an elongated opening 33 in the ring 20, thus allowing the ring 20 to slide idly past the screw 32. The overlapping portions 34 of the rings 19 and 20 are cut away or recessed, so that each ring is only of half thickness of the overlapping portions, this conducing to simplicity of construction, and enabling each ring to form half the V along the overlapping portion. 95

The toggle-joint is normally held in releasing relation, (Fig. 5) by means of a tension spring 35, which is anchored in a pin 36 on each link 25 and 26 of the toggle-joint 24.

In order to enable this spring to be effective to release the clutch formed by the toggle-joint, the toggle-joint is made of such length that it is never completely straightened out, thus permitting the spring 35 to 105 always have considerable tendency to release said joint. In order to hold the toggle-joint 24 normally released, the stub-shaft 27 is made long enough to extend into a detent cam plate 37, said cam plate 110 having a central detent notch 38 cut therein, into which the stub-shaft 27 rises when the spring 35 is permitted to release the toggle-joint 24.

The movement of the handle 17, in either direction, however, causes the V-shaped cam 28 to first draw the stub-shaft 27 out of the detent notch 38, thus causing the rings 19 and 20 to seize. Further movement of the handle carries the stub-shaft 27 along, carrying with it, of course, the platen, the movement continuing until the stub-shaft strikes the end 39 of the slot 40, which extends away from the notch 38. The slot 40 holds the toggle joint effective while the 120 handle 17 is moving the shaft 27, and the length of the slot 40 in either direction, determines how far the platen can be moved by the handle 17 when it is driving it by the shaft 27. 125

In order to draw the handle 17 to its normal ineffective position whenever released, there is mounted on an extension of the handle, and near its pivot, a pin 41 in 5 which is anchored a spring 42, the other end of said spring being anchored at 43 in the shift frame 8, the points 41 and 43 being so placed relatively to the shaft 30, that the spring 42 always tends to return the 10 handle 17 to such position, that it will carry the stub-shaft 27 into the detent notch 38; the line-space spring detent 11 aiding in this.

In order to protect the various parts from 15 catching on anything, the usual cover of the shift frame 8 is made to cover up the spring 42 and adjacent parts.

In order to give the mechanism sufficient 20 strength to bear the strains incidental to its operation, the shaft 30 is journaled in a block 44 forming a bearing extending substantially the whole length thereof, said block being extended to form the plate 37 in which the slot 40 is cut, and being also 25 extended at 46, to form a hold for the anchorage 43.

Variations may be resorted to within the scope of the invention, and portions of the improvements may be used without others.

Having thus described our invention, we 30 claim:

1. In a typewriting machine, the combination with a revoluble platen and a line-spacing mechanism therefor, of additional 35 line-spacing mechanism including a device normally ineffective on said platen for rotating it in either direction a fractional line-space, and including means encircling the platen to grip and rotate the same, means 40 also forming part of said additional mechanism for returning the platen to normal position when said mechanism is ineffective.

2. In a typewriting machine, the combination with a revoluble platen and line-spacing 45 mechanism therefor, of a friction clutch for said platen, a handle for rotating said clutch about the platen axis, a device normally holding said clutch released, means whereby said handle may be operated in 50 either direction, to cause said clutch to seize and then to rotate said platen frictionally a predetermined amount, and means for automatically returning said platen to its previous position when said finger-piece is released.

3. The combination with a revoluble platen and a grooved member thereon, of overlapping arc-shaped grooved V-rings, a 55 toggle-joint connecting said rings, and means for depressing said toggle-joint to cause said rings to seize said member.

4. The combination with a revoluble platen and a grooved member thereon, of overlapping arc-shaped grooved V-rings, a 60 toggle-joint connecting said rings, a pin 65

forming part of said toggle-joint, a cam in which said pin travels, and means for causing said toggle-joint to cause said rings to seize said member by moving said pin in said cam. 70

5. The combination with a revoluble platen and a grooved member thereon, of overlapping arc-shaped grooved V-rings, a toggle-joint connecting said rings, a pin forming part of said toggle-joint, a cam in 75 which said pin travels, and means for causing said toggle-joint to seize, by moving said pin in said cam, said cam including a cut-away portion, forming a detent opening to hold said joint released. 80

6. The combination with a revoluble platen, of a handle for turning said platen in either direction, a clutch forming a connection between said handle and said platen, and normally released from the platen, a 85 controlling-pin forming part of said clutch, a cam including a detent portion in which said pin normally rests and also including another portion effective on said pin to cause said clutch to seize, a spring normally tending to draw said handle to hold said pin at said detent, and a spring tending to hold said clutch released. 90

7. The combination with a revoluble platen, of a handle for turning said platen 95 in either direction, a clutch forming a connection between said handle and said platen, and normally released from the platen, a controlling-pin forming part of said clutch, a cam including a detent portion in which 100 said pin normally rests and also including another portion effective on said pin to cause said clutch to seize, a spring normally tending to draw said handle to hold said pin at said detent, a spring tending to hold 105 said clutch released, and a line-space detent normally holding said platen against revolving.

8. The combination with a revoluble platen, of arc-shaped rings encircling said 110 platen and overlapping to form a clutch, a toggle-joint at said overlapping portion for causing said rings to seize the platen, a handle connected to said toggle-joint, and means whereby movement of said handle in 115 either direction causes said toggle-joint to close said clutch and then carry the platen around by the handle.

9. The combination with a revoluble platen, of arc-shaped rings encircling said 120 platen and overlapping to form a clutch, a toggle-joint at said overlapping portion for causing said rings to seize the platen, a handle connected to said toggle-joint, means whereby movement of said handle in 125 either direction causes said toggle-joint to close said clutch and then carry the platen around by the handle, a pin forming part of said toggle-joint, a cam in which said pin travels and forming the closing means 130

whereby the handle is effective, and end portions on said cam, limiting the throw of said handle.

10. The combination with a revoluble platen, and a handle for turning it, of a clutch normally ineffective for enabling said handle to turn said platen, a cam for controlling the effectiveness of said clutch, said cam including a detent portion normally holding said clutch released, and a follower riding in said cam adapted to limit the throw of said handle and holding the clutch effective whenever the follower is free of the detent portion of the cam.
15. 11. The combination with a revoluble platen, and a handle for turning it, of a clutch normally ineffective for enabling said handle to turn said platen, a cam for controlling the effectiveness of said clutch, said cam including a detent portion normally holding said clutch released, a follower riding in said cam adapted to limit the throw of said handle and holding the clutch effective whenever the follower is free of the detent portion of the cam, said cam including a portion to permit the handle to be effective forwardly on the platen, and another portion to permit the handle to be effective rearwardly on the platen, and means normally tending to draw said handle to its ineffective position and to return the platen to the point from which the handle moved it.

12. In a typewriting machine, the combination with a platen and a line-spacing mechanism therefor, of a fractional line-spacing mechanism, comprising a finger-piece, a cam controlled by said finger-piece, means engaging with the platen, comprising a stud engaged by said cam, a slotted plate into which said stud projects, the ends of said slot acting as stops, to limit the movement of said finger-piece when the latter is moved forwardly or rearwardly from its normal central position, and a notch in said slotted plate for retaining said finger-piece in its normal position.

13. In a typewriting machine, the combination with a platen and a line-spacing mechanism therefor, of a fractional line-spacing mechanism, comprising a finger-piece, a cam controlled by said finger-piece, means engaging with the platen, comprising a stud engaging with said cam, and a plate

with which said stud engages, said plate limiting the movement of said finger-piece when the latter is moved forwardly or rearwardly from its normal position.

14. In a typewriting machine, the combination with a platen and regular line-spacing mechanism, of a fractional line-spacing mechanism, comprising frictional platen-engaging means, a lock to normally prevent the movement of said platen-engaging means to platen-engaging position, and a finger-piece for unlocking said platen-engaging means and cooperating with said platen-engaging means to rotate the platen fractionally a fractional line-space.

15. In a typewriting machine, the combination with a platen and regular line-spacing mechanism, of a fractional line-spacing mechanism comprising frictional platen-engaging means, a lock to normally prevent said means from moving to platen-engaging position, and a finger-piece connected to unlock said platen-engaging means and by further movement to cause rotation of said platen by said frictional platen-engaging means.

16. In a typewriting machine, the combination with a platen and regular line-spacing mechanism, of a fractional line-spacing mechanism comprising frictional platen-engaging means, a lock to normally prevent the movement of said means to platen-engaging position, and a finger-piece connected to unlock said platen-engaging means and simultaneously move said frictional platen-engaging means to platen-engaging position to drive the platen thereby.

17. In a typewriting machine, the combination with a platen and regular line-spacing mechanism, of a fractional line-spacing mechanism comprising frictional platen-engaging means, a lock to normally prevent the movement of said means to platen-engaging position, and a finger-piece connected to unlock said frictional platen-engaging means and simultaneously move the same to platen-engaging position, and by further movement to cause rotation of said platen thereby.
